US0D1111602S

(12) **United States Design Patent** (10) Patent No.: **US D1,111,602 S**
(45) Date of Patent: ** Feb. 10, 2026

(54) **PRODUCT DISPLAY UNIT**

- (71) Applicant: **Apple Inc.**, Cupertino, CA (US)
(72) Inventors: **Jean-Marc Gady**, Menlo Park, CA (US); **Gabriel J. Lamb**, Burlingame, CA (US); **Seung Chae Kang**, San Francisco, CA (US); **Angela M. Estepa**, San Francisco, CA (US); **Jake A. Nelson**, Berkeley, CA (US); **Adrian E. Magrina**, San Francisco, CA (US)
(73) Assignee: **Apple Inc.**, Cupertino, CA (US)
(**) Term: **15 Years**
(21) Appl. No.: **29/934,331**
(22) Filed: **Mar. 25, 2024**
